UNITED STATES PATENT OFFICE.

LOUIS N. D. WILLIAMS, OF OGONTZ, PENNSYLVANIA.

TAKE-UP DEVICE FOR KNITTING-MACHINES.

1,133,079.

Specification of Letters Patent. Patented Mar. 23, 1915.

Application filed June 13, 1912, Serial No. 703,433. Renewed August 15, 1914. Serial No. 856,988.

To all whom it may concern:

Be it known that I, LOUIS N. D. WILLIAMS, a citizen of the United States, residing in Ogontz, Montgomery county, Pennsylvania, have invented certain Improvements in Take-Up Devices for Knitting Machines, of which the following is a specification.

My invention relates to that class of belt driven take-ups for knitting machines in which the knitted web passes from the needle cylinder between a pair of take-up rolls, the weight of the latter, and of the operating devices therefor, hanging upon the knitted web so as to impart tension thereto.

The object of my invention is to so construct such take-up mechanism as to insure uniform tension upon the knitted web. This object I attain in the manner herein-after set forth, reference being had to the accompanying drawings, in which—

Figure 1 is a view, partly in side elevation and partly in vertical section, of sufficient of a knitting machine to illustrate one form of take-up mechanism constructed in accordance with my invention; Fig. 2 is a view, partly in elevation and partly in transverse section, on the line *a—a*, Fig. 1; Fig. 3 is a view similar to Fig. 1 but illustrating another and simpler embodiment of my invention; Fig. 4 is a sectional plan view on the line *b—b*, Fig. 3; Fig. 5 is a view partly in side elevation and partly in vertical section illustrating a still simpler embodiment of my invention; Fig. 6 is an enlarged sectional view of part of the same; Fig. 7 is a view partly in side elevation and partly in section illustrating the application of my invention to another type of machine than that shown in Figs. 1, 3 and 4; Fig. 8 is a plan or top view of the mechanism shown in Fig. 7; Fig. 9 is a view similar to Fig. 7 but illustrating some of the parts in a different position from that therein shown; Fig. 10 is a view similar to Fig. 7, but illustrating a construction of driving mechanism somewhat different from that therein shown; Fig. 11 is a view partly in side elevation and partly in section and on an enlarged scale of one of the members of the mechanism shown in Fig. 7; Fig. 12 is a view similar to Fig. 3, but illustrating means for actuating the take-up mechanism somewhat different from that shown in said figure, and Fig. 13 is an inverted horizontal section on the line *c—c*, Fig. 12.

In Fig. 1 of the drawing, I have illustrated my invention as applied to that type of circular knitting machine in which the needle cylinder rotates and the cam cylinder is stationary, but my invention is equally applicable to that type of machine in which the needle cylinder is stationary and the cam cylinder rotates.

In Fig. 1 of the drawings, 1 represents the fixed bed of the machine carrying the cam cylinder 2, and 3 represents the needle cylinder which is carried by a drive ring 4, the latter being rotatably mounted in the bed 1 and being provided with an annular rack 5 meshing with a spur wheel 6 on the main driving shaft 7 of the machine.

The take-up rolls 8 are mounted so as to rotate in bearings at the upper end of a frame comprising depending rods 9 and a cross head 10, constituting a take-up roll carrier which is free to rise and fall, the rods 9 passing through openings in a ring 11 which can turn in an intermediate member 12 of the fixed frame and is caused to rotate in unison with the needle cylinder 3 in any suitable manner, said ring being in the present instance connected to the drive ring 4 by any suitable number of depending bars 13. The rods 9 are also guided in openings in a flange 14 and in a cross head 15 located respectively at the upper and lower ends of a frame 16 secured to and depending from the ring 11.

One of the take-up rolls is rotated in one direction and the other in the opposite direction from a worm 17 at the upper end of a shaft 18 which is free to rotate in bearings 19 and 20, the upper bearing projecting from the take-up roll bearings and the lower bearing being secured to the cross head 10. Suitable gearing for driving the rolls 8 from the worm 17 is shown in Figs. 3 and 4.

The lower end of the shaft 18 is connected by bevel wheels 21 and 22 to a horizontal shaft 23 which turns in a bearing 24 depending from the cross head 10 and is provided at its inner end with a worm wheel 25, the latter meshing with a worm 26 (Fig. 2) on a short counter shaft 27 which turns in bearings in a bracket 28 depending from the cross head 10 and has at one end a star wheel consisting of a hub with projecting tappets 29.

Turning in suitable bearings 30 and 31, disposed upon the floor or other suitable

support beneath the take-up mechanism just described, is a shaft 32 which has at one end a pulley 33 and at the other end a bevel wheel 36. The pulley 33 receives a belt 34 from a pulley 35 on the driving shaft 7 of the machine, the latter pulley being shown by dotted lines in Fig. 1. The bevel wheel 36 meshes with a horizontal bevel wheel 37 free to turn on a stud 38 projecting from the top of the bearing 30, said bevel wheel 37 being provided on its upper face with a series of tappets 39 which travel in a circular plane intersected by the plane of rotation of the tappets 29, as shown in Fig. 2. The belt 34 is in permanent driving connection with the pulley 33 and consequently the shaft 32, and the bevel wheel 37 driven thereby, rotate continuously during the operation of the machine. When the knitted web is first applied to the take-up rolls 8, however, the latter and the operating mechanism therefor are elevated to such an extent that the tappets 29 are out of the path of the tappets 39 and the take-up rolls have no movement of rotation imparted to them but simply descend with the web of fabric as the latter is produced, the weight of the take-up rolls and their appurtenances exerting upon the web the necessary tension.

As the knitting of the web continues the take-up rolls and their appurtenances descend until finally the tappets 29 come into the path of the rotating tappets 39 and are in succession struck and moved by the latter so as to impart intermittent movements of partial rotation to the shaft 27 which movements are transmitted by means of the gearing hereinbefore described to the worm shaft 18 and thence to the gearing which rotates the take-up rolls 8, the latter therefore climbing upon the knitted web until the tappets 29 are again lifted above the path of the tappets 39, whereupon the rotation of the take-up rolls ceases until the lengthening web of fabric permits such further descent of said take-up rolls and their appurtenances as to again cause engagement of the tappets 39 with the tappets 29 whereupon the operations before described are repeated.

Heretofore, in take-up devices of the class to which my invention relates the shaft 32 carrying the belt pulley 33 has been mounted upon, and therefore partakes of the rising and falling movement of, the take-up roll carrier, the driving belt 34 being slackened or in non-driving contact with the pulley 33 when the take-up roll carrier rises and tightened or in driving contact with said pulley 33 when the take-up roll carrier descends. When the take-up roll carrier rises, therefore, the entire weight of the take-up rolls and their appurtenances is carried by the knitted web but when said take-

up roll carrier descends and the belt 34 is tightened into driving contact with the pulley 33 the weight is distributed between said belt and the knitted web, and consequently the tension upon the latter is slackened, and during the operation of the machine the tension upon the knitted web constantly varies.

In the take-up mechanism which I have just described, however, the shaft 32 is adapted to fixed bearings and the driving belt is always in driving connection with the pulley 33, the full weight of the take-up rolls and their appurtenances being always exerted upon the knitted web, consequently the tension upon the latter is uniform at all times.

Figs. 3 and 4 represent a somewhat simpler embodiment of my invention than that set forth in Figs. 1 and 2, and in these latter figures the parts constructed and operated as those set forth in Figs. 1 and 2 are correspondingly numbered. In the constructions shown in Figs. 3 and 4, however, the bars 13 which connect the drive ring 4 with the lower rotating ring 11 are forked at their lower ends so as to provide a pivotal support 50 for a swinging frame 51 which carries a pair of take-up rolls 52 geared together by a pair of spur gears 53 at one end as shown in Fig. 4, so as to rotate in opposite directions, the shaft of one of the take-up rolls also carrying a spur wheel 54 which meshes with another spur wheel 55 on a shaft 56 adapted to a bearing in a bracket 57 mounted upon a cross bar 58 on the swinging frame 51, said shaft also carrying a worm wheel 59 which meshes with the worm 17, the shaft 18 of the latter being mounted so as to turn freely in a bearing 60 carried by the bracket 57, as shown in Fig. 3. To the lower end of the shaft 18 is secured a disk 43 with projecting tappets 29 adapted to be struck and moved by tappets 39 projecting upwardly from a drum 61 which is free to turn on a stud 62, the latter being secured to and projecting upwardly from the ring 11.

The lower end of the drum 61 has a spur wheel 63 which meshes with a spur wheel 64 formed on the upper portion of a ring 65, the latter being carried by segments 11, fitted to an opening in the ring 11 and said ring 65 being recessed so that while it is free to turn on said segments it is vertically confined thereto. The lower end of the ring 65 is provided with a bevel wheel 66 which meshes with the bevel pinion 36 at the inner end of the shaft 32, as shown in Fig. 3. Chain wheels 33 and 35 take the place of the belt pulleys 33 and 35, shown in Fig. 1, and a chain belt will replace the plain belt 34 shown in said figure. The operation of this mechanism is as follows: The take-up rolls and the mechanism for driving the

same including the drum 61 and its spur wheel 63 all rotate with the knitting machine cylinder 3 and the ring 11 but the ring 65 has independent rotation imparted 5 to it preferably in a direction the reverse of that of the rotation of the ring 11 by means of the bevel pinion 36, consequently the drum 61 is caused to rotate upon its axis and the tappets 39 of said drum strike and move 10 the tappets 29 of the disk 43 whenever the latter tappets are in range of said tappets 39. This is dependent upon the rise and fall of the take-up rolls 52 with the knitted web delivered from the knitting machine cylinder. 15

The inoperative position of the rolls is that represented in Fig. 3 at which time the disk 43 is horizontal, its lower face being parallel with the upper face of the drum 61. 20 At such time the tappets 39 will pass the tappets 29 without contacting with the same. As soon, however, as the swinging frame 51 begins to swing downwardly from the position shown in Fig. 3 because of the lengthening web of fabric, that portion of the disk 43 which is closest to the take-up rolls also passes downwardly and therefore brings the tappet carried by that part of the disk into range of the tappets 39 of the drum 61, consequently each of the latter tappets imparts 25 a movement of partial rotation to the disk 43 and thence to the take-up roll operating mechanism so as to cause the latter to climb upon the web of fabric, this movement continuing until the parts are again in the position shown in Fig. 3 and the tappets 29 are out of the path of the tappets 39.

In order to prevent injury to the parts of the machine which might be caused by end 40 contact of the tappets 29 and 39, if both of said tappets were rigid, I prefer to mount the tappets 39 upon the drum 61 so that they can yield vertically therein, as shown in Fig. 3, each tappet 39 being adapted to 45 an opening formed in the drum 61 and said tappet resting upon a spring 67 at the bottom of said opening, longitudinal movement of the tappet being restricted by engagement of a projecting pin 47 thereon with the ends of the slot 48 formed in the drum 61.

Figs. 5 and 6 of the drawing show an embodiment of my invention which is still simpler than that shown in Figs. 3 and 4. In the construction shown in Fig. 5, I have 55 used the take-up rolls mounted in a frame 9 free to slide vertically through the ring 11, the main difference between this embodiment of my invention and that shown in the other figures of the drawing being in the simplification of the gearing whereby the take-up rolls are driven. The take-up rolls 8 are 60 geared together as before and the shaft of one of the take-up rolls has at one end a bevel wheel 70 which meshes with another bevel wheel 71 on the shaft 56 which car-

ries the worm wheel 59, both the shaft 56 and the worm shaft 18 being adapted to bearings in a bracket 72 projecting from one of the bars 9 of the vertically movable take-up frame. In this case the disk 43 carrying the tappets 29 is mounted upon the worm shaft and the actuating tappets 39 are carried by a ring 73 mounted so as to rotate in the fixed frame 12 of the machine and having beveled teeth which mesh with those of the bevel pinion 36 on the shaft 32, rising and falling movement of the take-up roll frame carrying the tappets 29 out of and into the path of the tappets 39 as will be readily understood. In this construction 70 a single spring 67 may serve to project diametrically opposite tappets 29 of the disk 43, this necessitating the offsetting of one pair of tappets in respect to the other, as shown in Figs. 5 and 6, and the tappets 39 75 being wide enough to engage with both sets of tappets 29.

In that form of my improved take-up mechanism shown in Figs. 7, 8, and 9, the take-up rolls are carried by a frame 40 having pivot pins 41 adapted to fixed bearings 42, said frame being free to swing upon its pivots 41 so as to rise with the take-up rolls as they climb upon the knitted web and descend with said rolls, as the web lengthens. 90 The worm shaft 18 carries a disk 43 which faces a disk 61 and carries tappets 29 for engaging tappets 39 projecting from the face of said disk 61, the latter being mounted upon the shaft 32, which carries the belt 100 driven pulley 33. When the parts are in the position shown in Fig. 7, the take-up rolls are non-rotative and descend with the knitted web, carrying with them the frame 40, and this causes the tappet disk 43 to 105 move toward the disk 61 until finally a tappet 29 at the lower portion of said disk 43 contacts with a tappet 39 while the latter is traversing the lower portion of its circular path (as shown in Fig. 9) and movement of 110 partial rotation is thereby imparted to the disk 43 and worm shaft 18 and thence to the take-up rolls, the latter therefore climbing upon the knitted web until they have raised the frame 40 sufficiently to again withdraw 115 the tappets 29 out of the path of the tappet 39. In this construction of take-up as in that shown in the other figures of the drawing, the shaft 32 occupies a fixed position and the belt 34 is always in driving contact 120 with the pulley 33 and at no time bears any portion of the weight of the take-up rolls and their appurtenances, such weight always being exerted upon the knitted web only.

In the construction shown in Fig. 10 a 125 tappet 39 is carried by a bevel wheel 44 occupying the same position as the disk 61 in the construction shown in Fig. 7, and geared by means of a bevel wheel 45 to the shaft 32 which constitutes a pivot shaft for the frame 130

40, the belt pulley 33 in this case occupying a position at a right angle to that which it occupies in the construction shown in Fig. 7, but the operation of the devices being in 5 other respects substantially the same.

Take-up mechanism of the types shown in Figs. 7 to 10 is intended for use in connection with a machine having a non-rotating needle cylinder.

10 In Fig. 11, I have shown means for yieldingly mounting the tappets 29 upon a disk 43 of the character represented in Figs. 7 to 10. Instead of yieldingly mounting the tappets upon a disk or other carrier, as de- 15 scribed, I may in some cases yieldingly mount the tappet disk or carrier itself, one means of accomplishing this result being shown in Fig. 9 and consisting of a spring 75 coiled around the shaft 32 and interposed 20 between the hub of the disk 61 and the bearing for said shafts 32.

In Figs. 12 and 13 I have shown a modification of my invention which permits of the use of change gears for determining the 25 speed of rotation of the drum 61. In this construction the fixed structure 12 has secured to it a spur wheel 76, the ring 11 being recessed for the reception of said spur wheel and said ring providing a bearing for the 30 shaft 77 of the drum 61, which shaft is provided at its lower end with a pinion 78 free from engagement with the spur wheel 76 but in driving connection, through the medium of an interposed spur wheel 79, with a 35 pinion 80 which is in mesh with the spur wheel 76, as shown in Fig. 13. The shafts of the pinion 80 and intermediate spur wheel 79 can be adjusted in slots in the ring 11 so as to permit of the use of larger or 40 smaller pinion 80 and thereby regulate the speed at which the shaft 77 and drum 61 are rotated.

I claim:

1. In take-up mechanism for knitting machines, the combination of a take-up roll carrier movable in the direction of delivery of the knitted web and take-up-roll driving mechanism having a driven member on the movable take-up-roll carrier, and a driving 50 member mounted in fixed bearings.

2. In take-up mechanism for knitting machines, the combination of a take-up-roll carrier movable with the knitted web, and take-up-roll driving mechanism having a driven member on the movable take-up-roll carrier, and a driving member therefor mounted in fixed 55

bearings, and connected to a belt pulley, another belt pulley mounted in fixed bearings on the machine and a belt connecting said pulleys.

3. In take-up mechanism for knitting machines, the combination of take-up-rolls and their appurtenances whose weight is carried by the knitted web, and a belt-actuated take-up-roll driver carried by a shaft which is 60 mounted in a bearing having no movement of rotation about the axis of the machine, said shaft having a pulley with which the belt is in continuous driving contact.

4. In take-up mechanism for knitting machines, the combination of take-up rolls and their appurtenances mounted in a movable carrier whereby the take-up rolls are free to rise upon or descend with the knitted web and cause their weight to exert tension upon 70 said web, and driving devices for the take-up rolls having as elements a tappet wheel on the movable take-up-roll carrier and a tappet wheel whose shaft is mounted in fixed 75 bearings.

5. In take-up mechanism for knitting machines, the combination of take-up rolls and their appurtenances mounted in a movable carrier whereby the take-up rolls are free to rise upon or descend with the knitted web 80 and cause their weight to exert tension upon said web, and driving devices for the take-up rolls having as elements a tappet wheel on the movable take-up-roll carrier and a tappet wheel on a belt driven shaft mounted 85 in bearings which do not partake of the movement of the take-up-roll carrier.

6. Take-up mechanism for knitting machines comprising take-up rolls for engaging the knitted web, and driving devices for 90 said take-up rolls having engaging tappets and means providing a yielding backing for one or more of said tappets.

7. Take-up mechanism for knitting machines comprising take-up rolls for engaging 100 the knitted web, and driving devices for said take-up rolls having as elements tappet wheels, one of which is provided with spring-projected tappets.

In testimony whereof, I have signed my 105 name to this specification, in the presence of two subscribing witnesses.

LOUIS N. D. WILLIAMS.
